US00D786347S

(12) **United States Design Patent** (10) Patent No.: **US D786,347 S**
(45) Date of Patent: ** *May 9, 2017

(54) **INK CARTRIDGE**

(71) Applicant: **BROTHER INDUSTRIES, LTD.**,
Nagoya-shi, Aichi-ken (JP)

(72) Inventor: **Naoya Okazaki**, Hashima-gun (JP)

(73) Assignee: **BROTHER INDUSTRIES, LTD.**,
Nagoya (JP)

(*) Notice: This patent is subject to a terminal disclaimer.

(**) Term: **15 Years**

(21) Appl. No.: **29/556,680**

(22) Filed: **Mar. 2, 2016**

(30) **Foreign Application Priority Data**

Sep. 2, 2015 (JP) 2015-19440

(51) LOC (10) Cl. **18-02**

(52) U.S. Cl.

USPC **D18/56**

(57) **CLAIM**

The ornamental design for an ink cartridge, as shown and described.

DESCRIPTION

FIG. 1 is a front, top, left-side perspective view of an ink cartridge;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof;

FIG. 8 is a rear, top, right-side perspective view thereof; and,

FIG. 9 is a front, bottom, left-side perspective view thereof.

The broken lines depict environmental subject matter only and form no part of the claimed design.

1 Claim, 8 Drawing Sheets
